CLAIM

The ornamental design for dosage packaging for washing agents, as shown and described.

DESCRIPTION

FIG. 1 is a top perspective view of a first embodiment for a dosage packaging for washing agents embodying the new design;

FIG. 2 is a bottom perspective view thereof;

FIG. 3 is a top side view thereof;

FIG. 4 is a bottom side view thereof;

FIG. 5 is a front-side view thereof;

FIG. 6 is a back-side view thereof;

FIG. 7 is a right-side view thereof; and

FIG. 8 is a left-side view thereof.

FIG. 9 is a top perspective view of a second embodiment for a dosage packaging for washing agents embodying the new design;

FIG. 10 is a bottom perspective view thereof;

FIG. 11 is a top side view thereof;

FIG. 12 is a bottom side view thereof;

FIG. 13 is a front-side view thereof;

FIG. 14 is a back-side view thereof;

FIG. 15 is a right-side view thereof; and,

FIG. 16 is a left-side view thereof.

The broken lines shown in the drawings depict portions of the dosage packaging for washing agents that form no part of the claimed design.
